UNITED STATES PATENT OFFICE

VICTOR R. HEFTLER, OF DETROIT, MICHIGAN, ASSIGNOR TO SOCIETE DU CARBURATEUR ZENITH, OF LYON, FRANCE, A CORPORATION OF FRANCE

CARBURETOR

Application filed September 3, 1926. Serial No. 138,365.

The present invention relates broadly to the art of carburation, and more particularly to improvements in carburetor structures of the character adapted for use with internal combustion engines.

At the present time it is recognized in the art to which the present invention relates that with ordinary carburetor constructions desirable mixtures are not produced at all speeds or under all conditions of operation. With at least most of the commercial carburetors there is a so-called "flat spot" at some one speed in the carburetor operation, this flat spot preventing that uniformity of motor operation or acceleration which is desired.

Many different attempts have been made to correct defects of the character referred to by improving the mixture characteristics either with respect to the fuel system or with respect to the air system. From the standpoint of the fuel system proposed corrections have contemplated the feeding of additional fuel at predetermined times. Corrective measures of this nature have contemplated either an auxiliary source of fuel supply, or a temporary enrichment of the usual fuel supply as shown, for example, in the patent to Mock, No. 1,395,233 of October 25, 1921.

Corrective measures as applied to the air system at the present time have usually been predicated upon increased efficiency in the suction producing means. Not infrequently recourse has been had to double venturis for this purpose. Experience has demonstrated, however, that while double venturis do give an increased suction and thereby effect a fuel flow at a correspondingly less air flow, and necessarily overcome the initial handicap sooner, they have a very decidedly objectionable operation throughout a portion of their range, which is usually at a speed of substantially fifteen miles an hour.

In most carburetors there is some difficulty involved in the change from operation with low throttle opening to operation with larger throttle opening, due to the fact that, in the first position, most of the fuel comes from idling holes positioned near the lower edge of the throttle, while at higher speeds it comes from nozzles located in the venturi.

This transfer of operations is not infrequently accompanied with irregularities in the mixture, whether the transfer be slow and gradual or sudden. In the construction of many present day carburetors the fuel supply for idling purposes is taken from an open well, fed through a restricted opening from the float chamber, and in which the level necessarily drops while the carburetor is in operation, so that the reserve of fuel which is depended upon for sudden acceleration is depleted by the idling jet. The present invention contemplates improved means for maintaining, during very low idling, a reserve of fuel at the normal level. This can be drawn upon in case of sudden acceleration, and by reason of its high level will be more easily drawn into the mixing chamber, while providing fuel for very low idling and without increasing the fuel delivery necessitated for compensation.

The present invention contemplates improved means for effecting the elimination of the so-called flat spots by improving the fuel supply and thereby obviating the necessity of utilizing double venturis or similar means with their attendant irregular suction multiplication factor at different speeds.

In the accompanying drawings there is illustrated a preferred embodiment of the present invention, it being understood that the drawings do not define the limits of my invention, as changes in the construction and operation disclosed therein may be made without departing either from the spirit of the invention or the scope of my broader claims.

In the drawings:

Figure 1 is a vertical sectional view through one form of carburetor constructed in accordance with the present invention;

Figure 2 is a vertical sectional view on the line II-II of Figure 1 looking in the direction of the arrows;

Figure 3 is a transverse sectional view on the line III-III of Figure 1 looking in the direction of the arrows; Figure 2 and Figure 3 being on a slightly enlarged scale;

Figure 4 is a detail sectional view on an 100

enlarged scale on the line IV-IV of Figure 1;

Figure 5 is a transverse sectional view on the line V-V of Figure 1 through the venturi and illustrating the arrangement of fuel nozzles;

Figures 6^a, 6^b, 6^c, 6^d and 6^e are detail sectional views, partly diagrammatic, on the line VI-VI of Figure 2;

10 Figures 7^a, 7^b, 7^c, 7^d and 7^e are views similar to those just referred to on either of the lines VII-VII of Figure 2;

Figures 8^a, 8^b, 8^c, 8^d and 8^e are similar views on the line VIII-VIII of Figure 2; and

15 Figures 9^a, 9^b, 9^c, 9^d and 9^e are similar views on the line IX-IX of Figure 2, it being apparent that successive views in each group of figures illustrate the parts in different operative position.

20 Figure 10 is a diagrammatic view showing the fluid passages from their source to the point where they enter the mixing chamber.

The present invention is illustrated in connection with a carburetor of the Zenith type 25 in which there is a suction nozzle responsive to the depression existing within the venturi and one or more supplemental nozzles designed to feed a substantially constant amount of fuel irrespective of suction to 30 thereby compensate for the low speed leaness of the suction nozzle. In carburetors of this type it has been customary to feed fuel to the low speed device from the atmospheric well. In operation the slow speed device lowers the fuel level in the atmospheric well during the idling of the carburetor, so that if the throttle is suddenly opened fuel must be drawn, not from the level represented by the normal level maintained in the float 35 chamber, but from the lower level established by the slow speed device in the atmospheric well. This results in a lag between the fuel and the air and the consequent production of a flat spot.

40 45 I have proposed to correct such an operation by providing a plurality of atmospheric wells each receiving fuel through a calibrated opening, and feeding the slow speed device from one of the wells. Experiments have 50 demonstrated the impracticability of such a construction, however, for the reason that the well serving the slow speed device soon becomes exhausted. This exhaustion cannot be 55 prevented as it is impractical to use a larger calibrated opening leading thereto inasmuch as the sum of the two calibrated openings to the two wells must bear a definite relation to the main nozzle, and as the calibrated opening which serves the well delivering to the 60 slow speed device is made larger the opening to the other atmospheric well must be made correspondingly smaller, and the refilling period for such other well has thereby been unduly increased.

65 In accordance with the present invention

an improved operating structure is provided while retaining all of the advantages of the two types of feed and the atmospheric wells.

Referring more particularly to Figure 10, the fuel flows from a fuel inlet 18 to a strainer 19 and from the strainer to a float chamber 6. The float chamber is connected by a conduit 21 to a main nozzle 22 in the mixing chamber 2. The mixing chamber is provided with a throttle 29 having openings 36 therein. The float chamber 6 is connected by separate conduits 26 to wells 32 and 27. The well 27 is connected by a conduit 24 to an auxiliary nozzle 37 in the mixing chamber 2 adjacent the main nozzle 22. The well 32 is connected by a conduit 25 to another auxiliary nozzle 38 also adjacent the main nozzle 22. The well 27 has a quill 28c leading to a chamber 39 which is connected by conduit 30' to an outlet 30 in the mixing chamber 2. The outlet 30 is located above the throttle 29. The well 32 is connected by a quill 33a, which is larger than the corresponding quill 28c, to a chamber 40 from which the fuel passes through the conduit 34' to an outlet 34 in the mixing chamber below the throttle 29.

25 An air valve 45 regulates the air supplied to the float chamber 6, the wells 27 and 32, and the chambers 39 and 40 in which the quills 28c and 33a are located. Air is supplied from the air valve 45 to the float chamber 6 through a conduit 58. Conduits 49 and 59 supply air to the chambers 40 and 39 respectively. A conduit indicated in Figure 10 as 54 and 51 supplies air from the air valve to the wells 32 and 27.

30 The air valve 45 is actuated in accordance with the position of the throttle 29 to supply air through the passages 49, 58, 59 and 54 and 51 in accordance with whether the motor is idling or is operating at slow speed or at 35 high speed. When the motor is idling fuel is supplied from the well 27 through the quill 28c, chamber 39 and conduit 30' to the outlet 30 in the mixing chamber. When the throttle is opened to a slight extent in order to make the motor operate at a slow speed, fuel is supplied from the well 32 through the quill 33a, chamber 40 and conduit 34' to the opening 34 in the mixing chamber 2. When the motor is operating at idling speed, no fuel is supplied from the wells 27 or 32 to the auxiliary nozzles 37 and 38, and no fuel is fed from the float chamber 6 to the main nozzle 22. The control of the flow of fuel through the conduits 30', 34', 24 and 25 is determined by the amount of air supplied through conduits 59 and 49 to the chambers 39 and 40. If air is supplied through the conduits 59 and 49 it lowers the suction in the conduits 30' and 34', and if air is also supplied to the wells 27 and 32 through the conduits 54 and 51, the fuel is caused to flow through the conduits 24 and 25 to the auxiliary nozzles 37 and 38.

It will be seen that each of the wells 27 and 32 has an outlet leading to an auxiliary nozzle in the mixing chamber. Each of these wells also has a quill which leads fuel to the mixing chamber when the motor is either idling or operating at low speeds. The detailed construction and operation of the carburetor will be understood from the following description taken in connection with the other figures of the drawings.

As illustrated in the drawings, a carburetor embodying this invention may comprise body sections A and B adapted to be secured together in any desired manner, and composed of the same or different materials as may be desired. Extending through the section B is an opening 2 forming a carbureting chamber and adapted to receive a venturi 3 suitably held in position therein as by a screw 4.

20 Air for the venturi is supplied through the inlet 5 in the section A.

Formed in the section A is a float chamber 6 adapted to receive a float 7 having a pivotal mounting 8 and effective for maintaining a constant level in the float chamber by co-operation with a valve stem 9. The valve stem is conveniently operated by providing an intermediate lever 10 having a suitable pivotal mounting 11 and adapted to engage the valve stem 9 upon upward movement thereof. The valve stem is mounted for movement in a holder 12 threaded upwardly into the laterally projecting shelf on the section B. At its upper end the valve stem 35 carries a ring 13 within which is located a ball valve 14 adapted to cooperate with the seat 15 for cutting off fuel supply to the float chamber. It is desirable to provide means whereby the inlet valve, its seat and holder 40 can be assembled as a sub-unit, tested as such, and that the distance D, Figure 1, from the seating face of the holder to the tip of the valve stem, when the valve is seated, be maintained at a standard value. This greatly facilitates the manufacturing and servicing of carburetors in the field. For this purpose the valve seat 15 is preferably formed on an inner member 16 slidably mounted in the nut 12. When the parts have been properly 45 adjusted, the nut and the inner member 16 may be secured in adjusted position by solder 50 17 or the like. It will be noted that the tip of the inner member 16 extends well up into the filter chamber so as to receive fuel from the upper position thereof instead of the lower position. This provides sort of a sump 55 into which dirt, water and the like may accumulate without possibility of being drawn into the vitals of the carburetor.

60 The fuel supplied to the carburetor may be obtained through an adjustable connection 18, as well understood in the art, delivering to a filter 19 located in a suitable recess 20 in the laterally projecting shelf.

65 Leading from the lower portion of the

float chamber is a passage 21 communicating at its lower end with a suction nozzle 22 through an opening 23. The outlet of the nozzle 22 may be suitably positioned within the venturi 3, and preferably at a point 70 slightly beyond the most restricted section of the venturi whereby it is subjected to the maximum depression obtaining therein.

Leading from the float chamber on opposite sides of the opening 21 are passages 24

and 25 respectively, each of these passages having the amount of fuel which passes therethrough controlled by a calibrated plug 26.

The passage 24 leads to a well 27 into which extends a quill assembly 28 adapted to supply fuel to a point above the throttle 29, an outlet opening 30 into the carbureting chamber being provided for this purpose. This assembly may be of any desired construction,

but preferably comprises a holder 28^a adapted to be threaded upwardly into the section B of the carburetor whereby it may be assembled therein before the sections A and B are put together. The lower end of the holder 28^a is tapped to receive the idling nozzle 28^b to which the tube 28^c, soldered thereto, supplies fuel from the lower portion of the well 27. The holder may also carry a tubular quill 28^d. The holder 28^a is preferably provided with openings 31 therein for admitting air into the fuel stream anterior to the point of discharge thereof whereby an emulsion is formed when the level of the fuel drops to such a point as to uncover the openings 31. The upper part of the well, as clearly shown in Figure 3, is quite large and thereby not only insures quite a supply of fuel for starting, but also delays the time at which the openings 31 are uncovered.

30 The passage 25 delivers to a second atmospheric well 32 into which extends a quill 33 mounted similarly to the quill 28 and delivering to the carbureting chamber through an outlet opening 34 preferably so located as indicated in Figure 1 that it is normally only partially covered when the throttle is in its closed position. The quill 33 may be provided with one or more openings 35 by means of which a predetermined amount of air may

35 be continuously passed to the fuel delivered through the opening 34.

The throttle is provided with openings 36 extending therethrough to permit the passage of a small amount of air which, however, is not enough for idling; the rest of the air is supplied by the two crescent-shaped openings left around the throttle when the latter is slightly opened. I prefer to choose the size of those holes 36 so that the throttle

40 need be opened only a few thousandths of an inch for idling. During this time the depression existing at hole 34 is effective for drawing fuel upwardly in the quill assembly 33 a predetermined distance, this distance

45 preferably being such that there is no

50 100

60 110

65 115

70 120

75 125

80 130

85

discharge of fuel through the outlet 34. As the throttle is cracked open it will be apparent that the edge of the throttle moves across the outlet 34 and thereby increases the depression to which the assembly 33 is subjected. The condition obtaining at this time is such that fuel will be drawn from the assembly 33 and will discharge into the carbureting chamber. If instead of gradually continuing the opening movement of the throttle, the throttle is suddenly opened, the absolute pressure to which the assembly 33 is subjected suddenly increases, thus stopping the feed of fuel from the outlet 34 at a time when the fuel level in the assembly 33 is materially above the normal level in the float chamber.

The well 27 is adapted to feed fuel into the venturi through an outlet nozzle 37, while the well 32 is adapted to deliver fuel into the venturi through a similar nozzle 38. Thus, when the suction at the edge of the throttle is insufficient to draw the fuel through the ports 30 and 34, fuel is fed to the carbureting chamber through auxiliary nozzles 37 and 38. When the fuel feed through the port 34 is stopped due to the sudden opening of the throttle, the additional head of fuel will be effective for temporarily increasing the fuel flow through the nozzle 38 and thereby temporarily enriching the mixture to such an extent that the formation of a flat spot is prevented.

It is obviously desirable to provide means for accurately controlling the characteristics of flow through the outlet openings 30 and 34. For this purpose there is provided a variable air inlet communicating with the chambers 39 and 40 surrounding tube 28^c and a similar tube 40 inserted in holder 33 respectively. Such a variable control of the air supply may be accomplished by the provision of needle valves 41 and 42 adapted for the respective control of air delivered through the openings 43 and 44 leading to the chambers 39 and 40. As more air is admitted to either of the chambers, the effect of the suction in the carbureting chamber on the respective quills will be lessened while a restriction in the amount of air will increase the suction effect.

I preferably provide common valve means whereby the flow of air to the respective carburetor parts, including the float chamber, the wells, and the chambers above the quills, may be controlled in certain predetermined relation. For this purpose I have shown a tubular valve 45 extending transversely through the carburetor body and as formed with open ends closed by air filtering means 46. The valve 45 may be actuated in any desired manner, as by a crank arm 47, as well understood in the art.

The tubular valve 45 is provided with openings 48 and 55 to control the air to the two low speed quills, with openings 50, 52 and 53

to control the air to the wells, and with openings 56 and 57 to control the air to the float chamber. With the valve 45 in the closed positions of Figures 6^a, 7^a, 8^a and 9^a, the float chamber is open to the admission of air, as in all other positions, but the channels to the wells are closed, as are also the passages to the air adjusting needles. This is the starting position of the parts.

In the next position, shown in Figures 6^b, 7^b, 8^b and 9^b, a little air is allowed into the wells, but none is allowed to enter the quills. This permits the fuel level to drop in the wells and reduces somewhat the amount of fuel fed to the quills. It is an enriching position from the normal. Air is still freely admitted to the float chamber.

The next position of the valve, as shown in Figures 6^c to 9^c, inclusive, permits a little greater admission of air to the wells.

Figures 6^d to 9^d, both inclusive, show a further position in which air is being admitted to the low speed quills and the air to the wells is increased.

In Figures 6^e to 9^e, both inclusive, there is shown the normal position with maximum air flow to the various parts controlled by the valve.

The foregoing operations are obtained by the connections hereinafter described in detail.

The opening 48 is adapted to gradually move into registration with a vertically extending passage 49 communicating with the opening 44 under the control of the needle valve 42. With the tubular valve in the position of Figure 6^a the opening 48 is out of registration with the passage 49. At this time no air will be supplied to the chamber 40 above the quill 3 and the quill will be subjected to the full depression existing below the throttle. As the valve moves into its next position, the opening 48 approaches but does not come into registry with the passage 49. As the valve 45 is further operated into the position illustrated in Figure 6^c, the edge of the opening 48 will be brought into communication with the passage 49. Thereafter continued movement of the valve in the same direction as illustrated in Figures 6^d and 6^e respectively, will gradually increase the amount of air delivered to the chamber 40 and correspondingly decrease the suction effect on the quill 33.

The opening or openings 50 are adapted with the parts in the position illustrated in Figure 6^a to be out of communication with an inclined channel 51, indicated in Figure 7^a, and leading downwardly into the space with which the wells 28 and 32 communicate, as shown by Figure 3. Movement of the valve to the position of Figure 7^b is still not effective for admitting atmospheric air to the wells, such communication being established when the parts reach approximately

the position of Figure 7^c. As the tubular valve continues to move in the same direction into the position of Figures 7^a and 7^c respectively, the amount of air admitted thereby to the wells will be increased.

The relatively small opening 52 and relatively larger opening 53 are adapted to control the flow of air through an inclined channel 54 similar to the channel 51 and also communicating with the space above the wells. With the valve in the position of Figure 6^a, the interior of the valve is out of communication with the channel 54, as clearly apparent from Figure 8^a. Movement of the valve to the first position brings the opening 52 into communication with the channel 54, thereby admitting a limited amount of air. In the position of Figure 8^c the opening 52 is in full communication with the channel 54, continued movement of the valve in the same direction moving the opening 52 out of registration of the channel 54 and gradually bringing the larger opening 53 into registration therewith.

The openings 55, 56 and 57 are located in the end of the valve opposite the opening 48 but in the same transverse plane. With the parts in the position illustrated in Figure 6^a the interior of the tubular valve will be in communication with the float chamber by reason of the fact that the opening 56 is in registration with the passage 58 leading to the float chamber. Thus atmospheric pressure exists in the float chamber at this time. As the valve is moved from the position of Figure 9^a to Figure 9^b the opening 56 gradually moves out of registration with the passage 58, and the opening 57 moves toward a position of registration with such passage. The opening 55 likewise moves toward a position of registration with passage 59 communicating with the passage 43 under the control of the needle valve 41. Continued movement of the valve 45 in the same direction into the position of Figure 9^c brings the opening 55 only into registration with the passage 59 and leaves the openings 56 and 57 both in communication with the passage 58. Continued movement in the positions of Figures 9^a and 9^c respectively, maintains communication with the float chamber and establishes communication with the passage 59 whereby air is admitted to the chamber 39 to counteract the effect of suction in such chamber.

It will be apparent from the foregoing that with the valve in closed or starting position no air is delivered to either the chamber 39 or 40, or to the space above the wells but that air is delivered to the float chamber. As the throttle is opened and the valve 45 moves to the position of Figures 6^b, 7^b, 8^b and 9^b, respectively, which figures all represent a common position of the valve 45, air is still kept from the chambers 39 and 40, a little

air is delivered through the opening 52 to the space above the wells, and atmospheric pressure is maintained in the float chamber. Movement of the valve 45 in the same direction as indicated in the group of Figures 6^c, 7^c, 8^c and 9^c respectively, increases the amount of air to the space above the wells without affecting the other conditions. Further movement of the valve into the position of Figures 6^d, 7^d, 8^d and 9^d establishes communication to the chambers 39 and 40 and increases the flow of air to the wells without cutting off the flow to the float chamber. In its final position as represented by the figures of the e group, there is a maximum air admission to all of the parts. This is desirable as at this time both of the wells are delivering all of their fuel through the nozzles 37 and 38 respectively and at this time atmospheric pressure should exist in the wells, or nearly so.

With a carburetor of the construction herein shown, it will be apparent that there are retained all of the advantages of a compound fuel supply system, including a constant flow per unit of time system, and a suction system with the additional advantages of correction of any tendency toward a flat spot. An accurate control for the supply of air to the various parts of the carburetor is also obtained in definite relation to the opening of the throttle and in such manner that a rich idling or low speed mixture is first supplied through the quill 28, which mixture gradually decreases in richness as the speed of the motor increases and ultimately ceases to function entirely as the feed transfers from the outlet opening 30 to the nozzle 37. As the throttle is gradually opened up to a certain predetermined point, the level of the fuel in the quill 38 gradually rises until at a predetermined throttle position fuel is delivered through the opening 34 to augment the low speed feeding device. As the throttle continues its opening movement the flow of fuel through the opening 34 ceases and the increased head of fuel established by reason of the previously existing suction becomes effective during the period of transition or sudden throttle opening for increasing the fuel delivery through the nozzle 38 and thereby facilitating acceleration. During these various operations the supply of air to the wells is accurately controlled, whereby initially pure fuel issues from the low speed feeding device, this fuel gradually changing to an emulsion, as will be apparent.

With a great number of carburetors as commonly constructed there is a very objectionable action frequently noticeable when, after running for some time on an open throttle, the throttle is suddenly closed. In some cases the motor supplied by the carburetor would actually stop. This is because of the fact that if the idling hole is located

too far above the level, when the throttle is returned to the idling position it takes too long for the fuel to come up. By the present construction I have provided a carburetor which runs smoothly during its entire range irrespective either of sudden throttle opening or closing. This I attribute not only to the features before referred to in detail, but also to the specific construction of the respective quill assemblies and the location of the gasoline holes therein, and especially the location of the low idling fuel delivery close to the normal fuel level. It will be noted that the quill 28^b is of comparatively small diameter and has its gasoline hole 28' located about at the fuel level, while the quill 33^a is of comparatively large diameter and has its gasoline hole 33' located well above the fuel level. By reason of this construction, the quill assembly responds very quickly to demands upon it in case of sudden throttle closing, thereby insuring recovery. This is necessarily true as the fuel does not have to be lifted any very appreciable amount, so that there is no lag in the fuel feeding operation therefrom. With the large quill 33^a however, there is a considerable amount of fuel held in the quill and available for dumping upon sudden throttle opening, to thereby insure smooth change from idling to running.

With the single quill construction heretofore provided these conditions have not been obtainable. In order to insure recovery with such constructions it has been necessary to make the quill of small diameter, and this has in turn materially limited the gasoline available for dumping upon sudden throttle opening. By the present arrangement, these two conditions are effectively reconciled, and this constitutes a highly advantageous feature of the present carburetor.

By reason of the operation set forth, an efficient mixture is provided by means of two slow speed feeding devices effective in certain predetermined relation, each having its own adjusting means, and preferably so arranged that one is operative for slow speed and the other for idling. This insures a desirable quality curve and also a sufficient fuel supply at all times to satisfy the dimensions of the associated motor. The unit valve assembly disclosed herein is described and claimed in my co-pending application Serial No. 288,670 filed June 27, 1928.

Further advantages arise from the provision of a plurality of quills of different characteristics, whereby opposed conditions are effectively reconciled.

Still further advantages arise from the unit inlet valve assembly and the ease of standardization thereof, and from the manner of withdrawing fuel from the filter chamber, whereby only clean gasoline passes to the vitals of the carburetor.

I claim:

1. In a carburetor, a carbureting chamber, a main supply of fuel thereto, a plurality of fuel wells, a nozzle delivering fuel from each of said wells to said carbureting chamber, there being supplemental openings from each of said wells for the delivery of fuel to said carbureting chamber above said nozzles, and quill assemblies of different fuel feeding characteristics for transferring fuel from the respective wells to the supplemental opening. 70

2. In a carburetor, a carbureting chamber, a main supply of fuel thereto, a plurality of fuel wells, and a nozzle delivering fuel from each of said wells to said carbureting chamber, there being supplemental openings from each of said wells for the delivery of fuel to said carbureting chamber above said nozzles, one of the supplemental openings being above and the other being below the throttle in said carbureting chamber. 80

3. In a carburetor, a carbureting chamber, a main supply of fuel thereto, a constant level chamber, a plurality of wells, a fuel feeding quill communicating with each of said wells for delivering fuel to said carbureting chamber independently of said main supply, and valve means for controlling the delivery of air to said float chamber, said wells and said quills. 90

4. In a carburetor, a carbureting chamber, a plurality of fuel feeding quills of different characteristics relative to fuel dumping leading to said carbureting chamber, and means for feeding fuel to said quills, said means comprising a well for each quill and means for controlling the air supply to said wells. 100

5. In a carburetor, a carbureting chamber, a fuel feeding quill of relatively small diameter, a fuel feeding quill of relatively large diameter, both of said quills having a discharge opening adjacent said throttle, and means for feeding fuel to said quills, said means comprising a well for each quill, there being an auxiliary nozzle in the carbureting chamber supplied by each of said wells and adapted to discharge fuel into said carbureting chamber a substantial distance below said throttle. 110

6. In a carburetor, a mixing chamber, a throttle therein, a main nozzle discharging into said chamber, a plurality of wells, an auxiliary nozzle communicating with each of said wells and effective under predetermined conditions to deliver fuel to said mixing chamber, and quills of different characteristics receiving fuel from said wells and delivering the same adjacent said throttle. 120

7. In a carburetor, a mixing chamber, a throttle therein, a main nozzle discharging into said chamber, a plurality of wells, an auxiliary nozzle communicating with each of said wells and effective under predetermined conditions to deliver fuel to said mix- 130

ing chamber, and quills of different characteristics receiving fuel from said wells and delivering the same adjacent said throttle, one of said quills being effective for dumping 5 a comparatively small quantity of fuel and the other for dumping a comparatively large quantity of fuel.

8. In a carburetor, a mixing chamber, a throttle therein, a main nozzle discharging 10 into said chamber, a plurality of wells, an auxiliary nozzle communicating with each of said wells and effective under predetermined conditions to deliver fuel to said mixing chamber, and quills of different characteristics receiving fuel from said wells and delivering 15 the same adjacent said throttle, one of said quills having its gasoline hole located materially lower than the other.

9. In a carburetor, a mixing chamber, a 20 throttle therein, a main nozzle discharging into said chamber, a plurality of wells, an auxiliary nozzle communicating with each of said wells and effective under predetermined conditions to deliver fuel to said mixing 25 chamber, and quills of different characteristics receiving fuel from said wells and delivering the same adjacent said throttle, one of said quills having its gasoline hole located materially lower than the other and 30 having a materially smaller diameter than the other.

In testimony whereof I have hereunto set my hand.

VICTOR R. HEFTLER.
